UNITED STATES PATENT OFFICE

WENDELL L. CARLSON AND RALPH S. HOLMES, OF SCHENECTADY, NEW YORK, AS
SIGNORS TO GENERAL ELECTRIC COMPANY, A CORPORATION OF NEW YORK

AMPLIFYING SYSTEM

Application filed January 28, 1927. Serial No. 164,341.

Our invention relates to systems wherein electrical impulses are amplified through means comprising a plurality of interconnected space discharge devices, such as thermionic amplifiers or the like, and has for its principal object the provision of an amplifying system which may be operated over a wide range of frequencies with a uniformly high degree of selectivity and with uniform amplification.

Our invention will be better understood from the following description when considered in connection with the accompanying drawings and its scope will be pointed out in the appended claims.

Referring to the drawings, Figs. 1 to 3 illustrate amplifying systems wherein our invention has been embodied; and Fig. 4 shows a plurality of curves relating to the operation of these systems.

Fig. 1 illustrates an amplifying system comprising space discharge devices 1 and 2 each provided with a cathode 3, an anode 4, a control grid 5, and a screen grid 6 which is arranged to practically eliminate the capacitative coupling between the control grid 5 and the anode 4. Suitable sources of potential, such as batteries 7, are provided for maintaining the screen grids 6 at predetermined potentials with respect to the cathodes 3 and like sources 8 are connected in the input circuits of the devices 1 and 2 for biasing the control grids 5 to potentials which ensure proper operation of these devices. Terminals 9 and 10 are provided for connecting the input circuit of the device 1 to the source of the electrical impulses which are to be amplified. Current is supplied to the output circuits of the devices 1 and 2 from sources 11 and 12.

It will be observed that the output circuit of the device 1 is coupled to the input circuit of the device 2 through a capacitative coupling 13 and an inductive coupling 14 which are preferably 180° out of phase with one another; that an inductance 15 and a capacity 16 are provided for tuning the output circuit of the device 1; and that an inductance 17 and a capacity 18 are provided for tuning the input circuit of the device 2.

In the present example, the capacitive coupling is provided between the high potential ends of said tuned circuits and the inductive coupling is provided at the low potential ends. The inductive coupling predominates and is opposed increasingly with frequency by the capacitive coupling which increases at a higher rate as will be seen hereinafter. The advantages of this combination of capacitative and inductive coupling between two tuned circuits will be readily understood upon consideration of Fig. 4. Such tuned circuits may not necessarily be provided between two electric discharge devices but may be any tuned circuits coupled in the same manner and for the same purpose.

Fig. 4 shows a curve "a" which indicates the effect of change in frequency on the amplification ratio from the input of tube 1 to the input of tube 2 when only the magnetic or inductive coupling 14 is used. Curve "b" shows the relation between frequency and the amplification ratio when only the capacitative coupling 13 is used. Curve "c" is the resultant of curves "a" and "b". This resultant curve indicates the effect of change in frequency on the amplification ratio when both the capacitative coupling 13 and the inductive coupling 14 are used with the capacity coupling 180° out of phase with the magnetic coupling. It will be observed that both couplings increase with frequency, and that the amplification ratio is substantially constant over a considerable range of frequencies and that the coupling tends to be lower at the higher frequency end of the range. The tuning of both the output circuit of the device 1 and the input circuit of the device 2 to the frequency of the impulses to be amplified has the marked advantage that only impulses having a frequency within the range of substantially uniform amplification are selected.

The screen grid tube possesses a very high impedance and accordingly it is possible to utilize a high impedance output circuit. The screen grid prevents coupling between the input and output circuits. This is advantageous because the tuning of the output circuit and the use of the compound coupling

does not increase the impedance of the output circuit beyond the value required to match the impedance of the screen grid tube, and the possibility of a substantially constant and uniformly high ratio of amplification is realized. The screen grid, the tuned output circuit and the compound coupling thus cooperate with one another to produce a high and uniform degree of amplification 10 and without regenerative feed-back from the output circuit of the tube to its input circuit.

Fig. 2 illustrates an amplifying system which differs from that of Fig. 1 in that the space discharge devices 19 and 20 are not 15 provided with screen grids, and in that a condenser 21 and coil 22, which is inductively related to the coil 15 and the coupling 14, are provided for neutralizing the capacitative coupling between the control grid 5 and the 20 anode 4 of the device 1.

Fig. 3 illustrates an amplifying system which differs from that of Fig. 2 only in that the neutralizing condenser 21 and coil 22 are connected between the control grid 25 5 and anode 4. It will be apparent that any suitable means other than those illustrated by Figs. 1 to 3 may be provided for neutralizing the capacitative coupling between the control grid 5 and the anode 4; and that the 30 advantages of the compound capacitative and inductive coupling between the two tuned circuits are not limited to the particular systems illustrated.

The embodiments of the invention illustrated and described herein have been selected for the purpose of clearly setting forth the principles involved. It will be apparent, however, that the invention is susceptible of being modified to meet the different conditions encountered in its use and we therefore aim to cover by the appended claims all modifications within the true spirit and scope of our invention.

What we claim as new and desire to secure 45 by Letters Patent of the United States, is:

1. The combination of a pair of space discharge devices including input and output circuits, means for tuning the output circuit of one of said devices and the input circuit 50 of the other of said devices, and capacitative and inductive couplings connected between said tuned circuits, said couplings being out of phase with each other and the capacitative coupling being between the high potential 55 ends of said tuned circuits.

2. The combination of a pair of space discharge devices each provided with an input circuit including a cathode and control grid and with an output circuit including a cathode 60 and anode, means for tuning the output circuit of one of said devices and the input circuit of another of said devices, and a coupling including a capacity and an inductance each coupled separately and independently between 65 said tuned circuits and arranged to

produce in said tuned input circuit potentials which are substantially 180 degrees out-of-phase with one another, the capacity being located between the high potential ends of said tuned circuits.

3. The combination of a pair of space discharge devices each provided with an input circuit comprising a cathode and control grid and with an output circuit comprising a cathode and anode, means for tuning the output circuit of one of said devices and the input circuit of the other of said devices, a compound capacitative and inductive coupling connected between said tuned circuits, the capacitative and inductive components thereof being arranged separately to provide voltages in said tuned input circuit which are substantially 180° out of phase with each other, and means including a screen grid associated with said output circuit for preventing capacitative coupling between said output circuit and the control electrode of the device connected with said output circuit.

4. The combination of a pair of space discharge devices comprising input and output circuits, means for tuning the output circuit of one of said devices and the input circuit of the other of said devices, and said circuits being capacitively and inductively coupled, the inductive coupling predominating and being in opposition to the capacitive coupling.

5. The combination of a pair of space discharge devices comprising input and output circuits, means for tuning the output circuit of one of said devices and the input circuit of the other of said devices to the same frequency, and said circuits being capacitively and inductively coupled, the inductive coupling predominating and being in opposition to the capacitive coupling.

6. In a multistage alternating current amplifier system, an interstage coupling means therefor providing capacitive and inductive coupling between said stages, the capacitive coupling being substantially 180° out of phase with the inductive coupling and both being adjusted so that the amplification ratio is rendered substantially uniform over a relatively wide range of frequencies, said adjustment being such that the inductive coupling predominates and that the capacitive coupling increases more rapidly with frequency than said inductive coupling.

7. The combination with a pair of electric discharge amplifier devices, of a coupling means therefor, said means including a tuned input circuit, and a tuned output circuit, said circuits being inductively and capacitively coupled, and said couplings being related in value and arranged in opposing phase relation to each other to provide a resultant compound coupling which causes the amplification through said coupling means to remain

substantially constant over a relatively wide range of frequencies.

8. A coupling means for interconnected high frequency circuits, said means including an input circuit and an output circuit, means for tuning said circuits to the same frequency, said circuits being inductively coupled at their low potential ends, and being capacitively coupled at their high potential ends in opposing phase relation to said inductive coupling.

9. The combination with a pair of electric discharge amplifier devices, of a coupling means therefor, said means including a tuned input circuit for one of said devices, a tuned output circuit for the other of said devices, said circuits being inductively coupled, and being capacitively coupled in opposing phase relation to said inductive coupling, and means associated with said output circuit for preventing capacitive coupling therewith through the device with which it is associated.

10. The combination with a pair of electric discharge amplifier devices, of a coupling means therefor, said means including an input circuit for one of said devices, an output circuit for the other of said devices, means for tuning said circuits to the same frequency, said circuits being inductively coupled, and being capacitively coupled in opposing phase relation to said inductive coupling, said inductive and capacitive couplings both being arranged to increase with frequency, and said capacitive coupling being arranged to increase with frequency more rapidly than said inductive coupling.

In witness whereof, we have hereunto set our hands this 27th day of January, 1927.

40 WENDELL L. CARLSON.
RALPH S. HOLMES.
